UNITED STATES PATENT OFFICE.

HARVEY T. LEE, OF CHICAGO, ILLINOIS.

IMPROVEMENT IN TOYS.

Specification forming part of Letters Patent No. 140,206, dated June 24, 1873; application filed April 14, 1873.

To all whom it may concern:

Be it known that I, HARVEY THOMAS LEE, of Chicago, in the county of Cook and State of Illinois, have invented a new and beautiful Toy; and I do hereby declare that the following is a full and exact description of the same, reference being had to the accompanying drawing and to the figures marked thereon.

This invention consists of a slotted cylinder, closed at one end, and provided with a whistle at the other, as will be fully described hereinafter.

Figure 1 represents a side elevation of my novel toy; Fig. 2, a sectional elevation of the same; Fig. 3, a plan view of the disks forming the whistle; and Fig. 4, a view showing the manner of use.

To enable others skilled in the art to make and use my invention, I will now proceed to describe fully its construction and manner of operation.

A represents a cylinder, constructed, preferably, of tin, about an inch in diameter, which is closed at one end with a semi-spherical cap, provided with a wire ring, a, or other suitable means for attaching the cord *a*¹. The cylinder is provided with the longitudinal slot *a*², and has, also, at its lower end, the disks *a*³ *a*⁴, having central orifices, as shown, these disks being located about a quarter of an inch apart, to form the chamber x.

The toy is used by whirling it in the air by means of a cord, as shown in Fig. 4, by which means air is drawn into the slot, and forced out through the openings in the disks, the latter acting as a whistle, and producing a variety of sounds, according to the varying position of the toy in the air.

If desired it may be used as a whistle by blowing into the slot.

Having thus described my invention, what I claim as new, and desire to secure by Letters Patent, is—

The toy, consisting of the hollow slotted cylinder, constructed as described, and provided with the whistle, as and for the purpose set forth.

In witness that the above invention is claimed by me I have hereunto set my hand and seal.

Chicago, March 31, 1873.
